POLISHING BLOCK FOR UNIFORM INSIGNIA

Malcolm W. Courser, La Grange, Ill.

Application March 1, 1954, Serial No. 412,981

8 Claims. (Cl. 15—268)

This invention relates to a block or jig to appreciably assist one in holding and handily polishing uniform insignia and more specifically provides a jig for positioning uniform insignia such as badges, buttons, belt buckles or the like for easy polishing of such insignia.

An object of this invention is to provide a polishing block for uniform insignia having sockets and complementary grooves for receiving the fastening pins of the insignia thereby retaining the insignia in position while polishing.

A further object of this invention is to provide a polishing block for uniform insignia which is constructed of a pair of pivotally attached elements having recesses in the adjacent sides thereof for forming a storage area for the polishing tools such as a polishing rag or the like.

Yet another object of this invention is to provide a polishing block for uniform insignia having finger gripping grooved side portions and recessed areas for receiving the uniform insignia of the upper and lower surfaces thereby providing an efficient and effective polishing block.

A still further object of this invention is to provide a polishing block for uniform insignia which is simple in construction, easy to use, convenient, well adapted for its purposes and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the polishing block of the present invention with the grooved surface facing upwardly;

Figure 2 is a perspective view of the polishing block with the belt buckle receiving recess facing upwardly;

Figure 3 is a transverse, vertical section taken substantially along the transverse center line of the polishing block of the present invention;

Figure 4 is a longitudinal vertical section taken partially substantially along the longitudinal center line of the polishing block and showing the details of construction of one of the longitudinal grooves; and

Figure 5 is a transverse vertical section taken substantially along section line 5—5 of Figure 4 showing the details of a modified form of polishing block.

Referring now specifically to the drawings, it will be seen that the numeral 10 generally designates the polishing block of the present invention including a generally rectangular block of material 12 having concave recesses 14 in opposite side portions for facilitating the gripping of the polishing block 10 by the person's fingers. The upper surface of the block of material 12 is provided with a pair of transversely spaced longitudinal grooves 16 that are parallel to each other and spaced unequally from the longitudinal center line of the block 12. The grooves 16 extend partially through the block 12 and

2

are of a depth to receive the fastening prongs 18 of a button 20 or other uniform insignia. A pair of sockets 22 are spaced on each side of the center of the block 12 and are disposed equally from the center point of the block 12. The sockets 22 are substantially the same depth as the grooves 16. Positioned at the center point of the block 12 is a bore or socket 24 extending completely through the block 12.

On the lower surface of the block 12 is a rectangular recess 26 disposed centrally of the surface and having oppositely disposed notches 28 in the vertical side walls of the recessed portion 26 for receiving a belt buckle and the sliding cam lock of the belt buckle. It will be seen that the long open ended socket 24 extends completely through the block 12 and is in communication with the central area of the recessed portion 26.

As specifically shown in Figure 5, the block 12 may be constructed of upper and lower members 30 and 32 having abutting faces and adjoining edges hingedly connected together by a hinge member 34 and retained in overlying relation by a latch member 36 on the side of the block 12 opposite to the hinge 34. The central portion of the abutting surfaces of the upper member 30 and the lower member 32 are provided with recessed portions 38 which form a receptacle for polishing tools such as a polishing rag or polish thereby facilitating the storage of these articles preparatory for use in polishing the uniform insignia.

In practical operation, the buttons 20 or the uniform insignia is placed with the fastening prongs 18 or the like in the sockets 22, grooves 16 or long socket 24 as desired thereby holding the uniform insignia in position while polishing. When necessary to polish a belt buckle, the recessed portion 26 is brought into the upper position wherein the belt buckle will be received in the recessed area 26. If the belt buckle is the type having a sliding cam, the vertical grooves 28 will receive the sliding cam thereby facilitating the positioning of the belt buckle in the recessed area 26. Obviously, the device may be made of suitable wood, plastic, metal or the like and in a particular size to facilitate the easy storage and accessibility of the polishing block 10. It will be seen that the polishing block of the present invention may be utilized for quick and efficient polishing of the various uniform insignia thereby eliminating the usual tedious polishing operation.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A polishing jig for uniform insignia comprising a block having flat top and bottom surfaces, a pair of longitudinal grooves in one flat surface of said block, a plurality of selectively usable sockets in said one flat surface, and a recessed portion in the opposite flat surface of said block, said grooves, sockets, and recess adapted to receive and position uniform insignia for polishing.

2. The structure as defined in claim 1 wherein said block is provided with concave side surfaces thereby providing finger gripping grooves.

3. The structure as defined in claim 1 wherein said block is provided with a centrally disposed bore and said sockets are longitudinally spaced on each side of said bore, said grooves being parallel and equally spaced from said bore.

4. The structure as defined in claim 1 wherein said

recessed portion is centrally disposed and provided with a vertical groove in each side wall for receiving and positioning a belt buckle.

5. The structure as defined in claim 1 wherein said block is constructed of upper and lower plates pivotally secured to each other along one edge and having releasable latch means at the other edge for selectively retaining said plates in overlying relation, the contacting surfaces of said plates having complementary recessed areas forming a compartment for storing polishing tools.

6. A polishing block for uniform insignia having fastening prongs comprising a polygonal block, at least one groove in one surface of said block, and a plurality of sockets in one surface of the block, said sockets being positioned at various distances from said groove for positioning uniform insignia by receiving the fastening prongs.

7. The structure as defined in claim 6 wherein said block is provided with a belt buckle receiving recess on the surface in opposition to said one surface, and a centrally disposed aperture extending completely through said block.

8. A portable and handily usable jig through the medium of which one may temporarily anchor and clean and polish military insignia, cap ornaments, and belt

buckles comprising a block, said block being of appreciable cross-section and rectangular in form and having flat top and bottom surfaces with longitudinally grooved vertical side surfaces, said bottom surface having a recess therein, said top surface being provided inwardly of the lengthwise edges with a pair of spaced parallel grooves opening through the opposite transverse ends of the block, said block being further provided in said top face with a plurality of relatively short longitudinally spaced sockets in alignment with each other and positioned between the respective grooves and spaced therefrom, and a relatively long bore extending completely through the top and bottom surfaces and registering centrally at one end with said recess, the opposite end portions of said bore constituting sockets and one end portion of the bore in longitudinal alignment with the first named sockets and located at the exact center of the top surface of the block.
